(57) **CLAIM**

The ornamental design for transfer board for physically disabled persons, as shown and described.

DESCRIPTION

FIG. 1.1 is an enlarged right-side view of a transfer board for physically disabled persons.

FIG. 1.2 is a front view thereof.

FIG. 1.3 is a perspective view thereof.

FIG. 1.4 is a top view thereof.

FIG. 1.5 is a bottom view thereof.

The broken lines illustrate portions of the transfer board for physically disabled persons that form no part of the claimed design.
